FIG. 1.

FIG. 2.

FIG. 3.

FIG. 5.

FIG. 4.

FIG. 1 is a front elevational view of a combined upending bed and desk or similar article, showing our new design in closed position;

FIG. 2 is a left side elevational view in closed position, the right side being substantially a mirror image thereof;

FIG. 3 is a top plan view in closed position;

FIG. 4 is a left side, top and front perspective view with the bed in closed position and the desk in opened position; and

FIG. 5 is a left side elevational view with the bed in opened position and the desk closed, the opposite side being substantially a mirror image thereof.

The back, not shown, is substantially flat and unornamented. Portions of the drawing figures are shaded to indicate contrast in appearance.

We claim:

The ornamental design for a combined upending bed and desk or similar article, as shown and described.
